Inventor:
Charles H. Roberts

UNITED STATES PATENT OFFICE.

CHARLES H. ROBERTS, OF MITCHELLVILLE, IOWA.

PORTABLE WINCH.

SPECIFICATION forming part of Letters Patent No. 644,870, dated March 6, 1900.

Application filed September 12, 1899, Serial No. 730,282. (No model.)

To all whom it may concern:

Be it known that I, CHARLES H. ROBERTS, a citizen of the United States, residing at Mitchellville, in the county of Polk and State 5 of Iowa, have invented a new and useful Portable Winch, of which the following is a specification.

One object is to provide a simple, strong, and durable winch that will stand upright 10 when not in use and that is specially adapted to be applied to the end of a wagon-box for hoisting the box or to a fence-post for stretching fence-wire in such a manner that arms or branches extending laterally from the vertical centers of the ends of the frame will prevent tilting or lateral motion of the winch 15 when power is applied as required in practical use.

A further object is to reduce friction and 20 wear of the rope relative to the frame as it is wound off and on the drum.

My invention consists in the frame and arrangement and combination of operative parts therewith, as hereinafter set forth, pointed out 25 in my claim, and illustrated in the accompanying drawings, in which—

Figure 1 is a perspective view of the frame adapted for combining operative mechanism therewith to produce a simple portable winch 30 and to serve as an extended bearing to engage the end of a wagon-box, a fence-post, or other object. Fig. 2 shows my invention applied to the end of a wagon-box, as required for elevating the box, when the rope connected 35 with the winch is also connected with some elevated stationary object. Fig. 3 shows my winch detachably connected with a fence-post to draw and stretch wire, as required in making and repairing wire fences.

The metal frame is preferably malleable iron formed in a mold and may vary in size and weight, as desired. The two mating sides A and A² are straight and uniform, and each has laterally inclined and tapering 40 branches B and B² and a journal-bearing C at the juncture of the branches adapted for mounting a rotatable shaft therein, and each end of the frame is flat and adapted to engage and rest securely upon or against a fence-post or similar stationary object adapted to serve as a base upon which to operate my invention advantageously for various purposes. 45

The outer ends of the branches are connected by flat curved cross-bars D and D², and at the center of each of said bars is an aperture for 55 extending a rope or chain therethrough.

F is a cross-bar connecting the top ends of the straight parallel sides A and A². It is flat-faced and curved laterally and provided with an aperture H at its center for the passage of a rope J, that is fixed to a rotatable shaft K, that has journals on its ends fitted in the coinciding bearings C in the frame. By curving the cross-bar F the rope extended through the aperture H and fixed to the shaft 60 K will be retained straight in line with the exterior of the drum or shaft and will not bind and wear by friction in the aperture through which it is drawn while being wound on and off the drum or shaft K. A ratchet-wheel l 65 is fixed on one end of the shaft K, and a spring-actuated pawl m is attached to the branch B of the frame to engage the ratchet-wheel, as required to thereby lock the shaft K. A crank-handle r is placed on the end of the 70 shaft K for rotating the shaft and operating the winch by hand. Ropes s and s' are fastened in the apertures in the cross-bars D and D² and adapted to be detachably connected with the corners of a wagon-box, as shown in 75 Fig. 2, or in any suitable way as required for hoisting the wagon-box.

In Fig. 3 a chain s'', provided with a hook s''', is substituted for the ropes s and s'. (Shown in Fig. 2.)

J² is a clutch device fixed to the end of the rope J for detachably fastening a fence-wire J³ thereto, as required to stretch the wire.

Having thus described the construction and application of my invention to different objects for different purposes, its practical operation and utility will be readily understood by persons familiar with the art to which it pertains, and

What I therefore claim as new, and desire 95 to secure by Letters Patent therefor, is—

A portable winch comprising a frame composed of two vertical parallel sides having branches extending laterally and in opposite directions at their lower ends and journal-bearings at the juncture of said branches, the branches connected at their outer ends and the tops of the parallel sides connected by a cross-bar curved in a horizontal plane so that

its center lies directly above the edge of the drum, said bar having an aperture to admit and direct the passage of a rope relative to the exterior of a drum, a drum or rotatable shaft mounted in the said bearings in the frame, a ratchet-wheel fixed to the end of the shaft, a spring-actuated pawl attached to the frame and a crank-handle on the end of

the shaft or journal extended outside of the frame, all arranged and combined for the purposes stated.

CHARLES H. ROBERTS.
